UNITED STATES PATENT OFFICE

BERTRAND L. ABORN, OF BELFAST, MAINE

ROTARY SAW

Application filed October 11, 1929. Serial No. 398,923.

The present invention relates to a rotary saw and has for its prime object to provide a mechanism whereby a rotary saw or the like may be operated by connection with an 5 electrically operated drill or the like.

Another very important object of the invention resides in the provision of an operating mechanism of this nature which is simple in its construction, compact and convenient 10 in its arrangement of parts, strong and durable, thoroughly efficient and reliable in use and operation, handy, and otherwise well adapted to the purpose for which it is designed.

15 With the above and numerous other objects in view as will appear as the description proceeds, the invention resides in certain novel features of construction, and in the combination and arrangement of parts as 20 will be hereinafter more fully described and claimed.

In the drawing:

Figure 1 is a top plan view of the mechanism embodying the features of my invention, 25

Figure 2 is a longitudinal section therethrough taken substantially on the line 2—2 of Figure 1,

Figure 3 is a transverse section taken substantially on the line 3—3 of Figure 1,

Figure 4 is an end elevation of the mechanism.

Figure 5 is a side elevation thereof,

Figure 6 is a detail section taken substantially on the line 6—6 of Figure 1,

Figure 7 is a perspective view of the sleeve.

Figure 8 is a perspective view of the depth gauge, and

Figure 9 is a perspective view of the spindle.

Referring to the drawing in detail it will be seen that the numeral 5 denotes a bearing having a reduced portion over which one end of a sleeve 6 may be disposed and locked in place by means of a set screw 7. There is journaled in the bearing 5 a shaft 8 and the end of this shaft within the sleeve 6 has formed therein a square socket 9 while on the other end of the shaft there is fixed a 50 beveled gear 10.

Arms 11 and 12 extend from opposite sides of the bearing and are curved forwardly and terminate respectively in bearings 14 and 15. A shaft 16 is journaled in the bearings 14 and 15 to be at right angles to the shaft 55 8 and has a beveled gear 17 thereon in mesh with the beveled gear 10.

On the end of the shaft 16 to the outer side of the bearing 14 there is mounted a circular or disk saw 18 or any other suitable 60 or desired tool and this saw is held in place by means of a nut 19 threaded on said end of the shaft. An L-shaped depth gauge 19 has its shorter leg extended through an opening in the bearing 15 and is adjustably 65 locked in place by means of a set screw 20 so that the longer leg extends along the shaft 16 the desired distance therefrom.

A sleeve 22 is slidable on the longer leg of 70 the depth gauge 19 and held in different adjusted positions by means of a set screw 23. A width gauge 24 is mounted on the sleeve 22. A shield 25 is disposed over the upper portion of the saw 18 and held in this position by means of bracket 26 secured to one side of the 75 sleeve 6.

In the present exemplification of the invention the sleeve 6 is secured on an electric drill 27 by means of a set screw 28 so that the chuck 29 of the drill is disposed inside the 80 sleeve 6 and has one end of a spindle 30 locked therein, the other end thereof being squared as at 31 and received in the socket 9.

Thus it will be seen that when the electric 85 drill is turned on, the spindles 30 will be rotated thereby rotating the shaft 9, the gears 10 and 17 and the shaft 16 to rotate the saw 18. Although I have specifically exemplified the invention herein with the saw it is to be understood that other rotary tools 90 may be substituted therefor.

It is thought that the construction, operation, utility and advantages of this invention will now be quite apparent to those skilled in this art without a more detailed description 95 thereof.

The present embodiment of the invention has been disclosed in considerable detail merely for the purposes of exemplification 100 since in actual practice it attains the features

of advantage enumerated as desirable in the statement of the invention and the above description.

It will be apparent that changes in the details of construction, in the combination and arrangement of parts may be resorted to without departing from the spirit or scope of the invention as hereinafter claimed or sacrificing any of its advantages.

10 Having thus described my invention, what I claim as new is:

A saw of the character described comprising a supporting sleeve, a bearing in one end thereof, arms projecting from opposite sides 15 of the bearing, aligned bearings on the free ends of the arms, a shaft extending rotatably through the aligned bearings, means operatively connecting the shaft to a source of power for actuation thereby, a saw fixed on 20 the shaft adjacent one of the aligned bearings, a substantially L-shaped depth gauge having one of its legs extending for sliding adjustment through the other aligned bearing, the other leg of the depth gauge disposed 25 parallel to the shaft and terminating in spaced relation to the saw, means for securing the depth gauge in adjusted position, a sleeve mounted for longitudinal sliding adjustment on said other leg of the depth gauge, means 30 for securing the sleeve in adjusted position, and a width gauge formed integrally on the sleeve and extending therefrom in parallelism with the other leg of the depth gauge.

In testimony whereof I affix my signature.
